UNITED STATES PATENT OFFICE

WILLIAM F. CALDWELL, OF HOT SPRINGS, ARKANSAS

ODORLESS AND FLYPROOF DRY CLOSET

Application filed October 24, 1929. Serial No. 402,274.

This invention relates to a dry toilet and generally aims to provide a novel inexpensive and improved construction which is odorless and fly-proof.

5 A particular object is to provide a novel construction wherein a draft is created to carry off odors into the atmosphere and a construction which is compact and adapted for arrangement at a wall of a room.

10 Another object is to provide a construction wherein the seat opening is normally closed by a fly-excluding member and which is adapted to be opened by the pressure of the foot of an occupant.

15 The more specific objects and advantages will become apparent from a consideration of the description following taken in connection with accompanying drawings illustrating an operative embodiment, and wherein:—

20 Figure 1 is a view showing the improved toilet in central vertical transverse section in connection with part of a room,

Figure 2 is a view showing the improvements essentially in front elevation but partly broken away and in connection with portions of the room structure shown in section,

25 Figure 3 is a central vertical section through the toilet taken at a right angle to Figure 1, and

30 Figure 4 is a detail cross sectional view taken on the line 4—4 of Figure 2.

Referring specifically to the drawings, the toilet is preferably embodied in a room as conventionally shown at 10, the floor being 35 designated 11 and for instance supported by a sill 12 on masonry 13. Disposed mainly outwardly of the building or room but extending partly into the same is a casing preferably of metal, which is reenforced adjacent the top by batons 15 and 16, supporting a seat 17 having the usual opening 18 therethrough, the batons resting and being supported on bars 19 fastened to side walls of the room or building.

45 Within the casing 10 resting on the bottom thereof is a removable catch basin or receptacle 20, open at the top, and which may be removed laterally through an opening of the casing normally maintained closed by a door 50 21 of conventional form, which may be slid-

ably mounted in grooved rails 22 fastened to the casing.

Above the basin 20, the casing has inclined deflector plates 23 and 24 adjacent the front and rear thereof, respectively, and the casing rearwardly of the deflector 24 extends inwardly and upwardly at a wall 25 to provide a vent duct 26 which decreases in width in an upward direction as best shown in Figure 2, terminating in a nipple 27, onto which is removably telescoped or fitted a flue 28 discharging directly into the atmosphere.

55 As a result of the construction described, the atmosphere creates a suction through the opening 18 intermediate the deflectors 23 and 24 and thence upwardly rearwardly of the deflector 24 through the passage 26 and duct 28, thus removing odors.

60 In addition, a shield or closure plate 29 is provided to normally close the opening 18 against the entrance of flies, such shield or closure 29 preferably having a vent 30 provided therethrough. Shield 29 is rigid with a rod 31 journaled in a bearing 32 on the seat 17 and also journaled in the front wall of the 65 casing 14 and the baton 15. Forwardly of the baton 15, the rod 31 has a crank 33 to which a pitman 34 is pivoted and which is also pivoted at 35 to a treadle 36 pivoted at 70 37 to the previously mentioned floor 11. A 75 blade or leaf spring 38 is fastened to such floor and urges the treadle 36 upwardly as shown in the dotted lines in Figure 2 so that the plate or shield 29 covers the opening 18.

80 It will be realized that the occupant of seat 17, will arrange his feet in engagement with treadle 36 in order to maintain the opening 18 unobstructed, that is with the shield 29 in vertical or open position as shown in Figures 1 and 3. Upon the treadle 36 being released, 85 the spring 38 will immediately cause the shield 29 to close opening 18.

90 Various changes may be resorted to provided they fall within the spirit and scope of the invention.

95 I claim as my invention:—

1. A toilet of the class described having a casing, a seat on said casing, a deflector within the casing, said casing having a wall extending upwardly and inwardly toward the 100

deflector and thence upwardly forming an outlet for odors.

2. A toilet of the class described having a casing, a seat on said casing, a deflector within the casing, said casing having a wall extending upwardly and inwardly toward the deflector and thence upwardly forming an outlet for odors, the wall of the casing being extended upwardly from said deflector and last mentioned wall and terminating in a nipple, and a flue telescoped with said nipple.

3. A toilet of the class described having a casing, a seat on said casing, a deflector within the casing, said casing having a wall extending upwardly and inwardly toward the deflector and thence upwardly forming an outlet for odors, a deflector adjacent the front of the casing, and a catch basin within the casing below said deflectors.

20 In testimony whereof I affix my signature.
WILLIAM F. CALDWELL.
